UNITED STATES PATENT OFFICE.

EDWARD J. THURBER, OF NEW ORLEANS, LOUISIANA, AND JOHN W. RACKLYEFT, OF DETROIT, MICHIGAN, ASSIGNEES, BY MESNE ASSIGNMENTS, TO NORTHERN ENGINEERING WORKS, OF DETROIT, MICHIGAN, A CORPORATION OF MICHIGAN.

STARTER FOR INTERNAL-COMBUSTION ENGINES.

1,185,147.

Specification of Letters Patent. Patented May 30, 1916.

Application filed December 17, 1914. Serial No. 877,831.

To all whom it may concern:

Be it known that we, EDWARD J. THURBER, a citizen of the United States of America, residing in New Orleans, parish of Orleans, State of Louisiana, and JOHN W. RACKLYEFT, a citizen of the United States of America, residing at Detroit, county of Wayne, and State of Michigan, have invented certain new and useful Improvements in Starters for Internal-Combustion Engines, of which the following is a specification, reference being had therein to the accompanying drawings.

The invention relates to starters for internal combustion engines and more particularly to rotary starters of the type actuated by a compressed fluid.

The invention has among the objects thereof to provide a simple and efficient starting mechanism; to provide a starting mechanism that is compactly arranged and comparatively light, so that the apparatus will not take up any unnecessary room or add much weight to the engine. Further to provide an apparatus in which the parts are compactly arranged within the casing so as to form a single unitary structure for attaching to or detaching from the engine.

Other objects of the invention will more fully hereinafter appear.

The invention resides in the peculiar construction, arrangement and combination of parts as hereinafter set forth and as particularly pointed out in the claims.

In the drawings,—Figure 1 is a central vertical longitudinal section of a starting mechanism embodying the invention; Fig. 2 is a section on the line 6—6 of Fig. 1 with certain parts broken away; Fig. 3 is a section on the line 3—3 of Fig. 1; Fig. 4 is a section on the line 4—4 of Fig. 1; Fig. 5 is a section on the line 5—5 of Fig. 1.

The invention is primarily designed for use on automobile and marine engines of the explosion or combustion type, and generally embodies in a compact structure a fluid-operated rotary motor, a transmission mechanism and other suitable elements.

Referring to the one embodiment of the invention shown in the drawings, 1 designates the casing, divided by a web or partition 2 into two chambers. Within one of the chambers is arranged a rotary motor, while

in the opposite chamber is arranged the transmission and clutch mechanism. In the structure illustrated, the casing upon one side of the web is provided with an annular rim 3 that is disposed eccentric with relation to the shaft bearing 4 in the web, while connected to the outer edge of the rim 3 as 60 by screws 5 is a cap plate 6, the latter forming with the rim 3 and the web 2 a chamber for the rotor. The inner peripheral wall 6' of this chamber—as will be noted upon reference to Figs. 1 and 3—is eccentric to the shaft bearing 4. The rotor consists of a web 7 having an inwardly-extending flange 8 arranged concentric to the hub 9 of the web 7.

10 are the blades of the rotor, three being 70 herein shown, which are arranged for longitudinal movement in slots 11 in the web 7 and flange 8. The latter and the blades 10 are of a width to nicely fit between the web 2 and plate 6. As shown in Fig. 1, the 75 blades are provided adjacent their lower ends with cut away portions 12 which are adapted to engage a ring 13 arranged to travel within an annular guide groove 14 in the flange 8. This ring is free and acts as a 80 means for causing the blades to move outwardly. The hub 9 of the rotor is keyed at 15 to a sleeve 16 that is journaled in the bearing 4 carried by the web 2.

17 is the inlet for the rotor chamber and 85 18 the exhaust. Upon admission of a compressed fluid to the chamber of the rotor the latter will be set in rotation. During the rotation of the motor the inner peripheral face 6 and the ring 13 will—because they are 90 eccentric to the flange 8—cause the blades to be reciprocated longitudinally, as will be readily understood. During the rotation of the motor the sleeve 16 will turn therewith.

The transmission mechanism is herein 95 shown as of the planetary type. Thus journaled upon stub shafts 19 are pinions 20, which are in constant mesh with an internal or rim gear 21. The latter is carried by a disk 22 which is connected by means of 100 screws 23 to a member 24 that forms a part of a clutch.

25 is the other clutch member which is keyed to a shaft 26 that is free to rotate in the sleeve 16.

105 28 are spring-pressed dogs which in one

direction of rotation of the member 24, are adapted to lock said member to the member 25, while in the opposite direction of rotation will disconnect the members 24 and 25.

5 As shown in Fig. 1 the sleeve 16 is provided with a portion that projects within the transmission mechanism housing, and this portion of the sleeve is provided with a pinion 29 that meshes with the pinions 20.

10 30 is a shaft journaled in a bearing 31 and fixed to rotate with the shaft 26, the shaft 30 in effect forming a continuation of the member 26.

15 The transmission mechanism chamber is closed by a cap member 32 that is connected by means of screws 33 to the edge 34 of an annular flange 35 extending laterally from the web 2 and concentric with the bearing 4. The cap 32 is provided with a recessed or

20 chambered portion 36 within which is arranged the clutch mechanism and this cap carries at its outer end the bearing 31. Detachably connected to the cap of the rotor chamber is a pump housing 37 within which

25 is arranged a pump 38, the pump housing being attached to the cap by means of bolts 39. As shown, the end of the driven shaft has a portion 40 projecting within the pump housing and splined or otherwise suitably

30 connected to a sleeve 41 journaled adjacent its outer end in a bearing 42. The pump is provided with an eccentric 43 having a bearing 44 journaled upon the sleeve 41 and the latter and the bearing 44 are adapted

35 to be coupled together by means of a clutch member 45 free to slide upon the sleeve 41 but secured thereto against rotation, and having teeth 46 adapted to engage teeth 47 on the bearing 44. As the detailed construction

40 of the pump mechanism does not form a part of the invention of this application, a description thereof will not be given. The outer end of the pump casing is closed by means of a cover plate 48 and preferably

45 the outer end of the sleeve 41 is provided with a crank-engaging portion 49 for receiving the usual starting crank in case the rotary starter becomes inoperative. Normally the crank-engaging portion 49 is in-

50 closed by means of a cap 50.

As before stated, the sleeve or driving shaft 16 is journaled in a bearing carried by the web or partition 2. This bearing in the structure illustrated projects laterally 55 from the partition into the chamber of the rotor, this being permitted by the cut-away portions of the plates or pistons. As shown in Fig. 1, the openings between the several chambers in the casing are all suitably 60 sealed by packing material.

In operation, assuming that the portion 30 is fixedly connected to the engine shaft when compressed air or other compressed fluid is admitted into the rotor chamber, the ro- 65 tor is started in motion, which turns the

sleeve or drive shaft 16. The drive shaft, through the medium of the pinion 29, rotates the pinions 20 and the latter impart motion to the internal or rim gear 21, and since the disk 22 carrying the internal gear 70 is fixedly connected to the part 24 of the clutch, the latter is rotated. The direction of rotation of the member 24 is such as to cause the dogs to couple the members 24 and 25 together and since the member 25 is secured to rotate with the shaft 26, the latter is actuated and drives the extension 30 and through the latter, the crank shaft. When the engine is started the speed of rotation of the shaft 30 is greater than that of the drive 80 shaft 16, which causes the dogs to allow the member 24 to be disconnected from the member 25.

The pump is employed for storing compressed air in a tank or other chamber, as 85 will be readily understood, and normally is disconnected from the shaft 26. During the operation of the engine, when it is desired to add compressed air to the tank the clutch member 45 is longitudinally shifted through 90 the medium of a lever 51, to cause the pump to be coupled to the sleeve 41 that is splined to the shafts 26.

From the foregoing description it will be readily understood that a starting mechanism embodying the invention forms a very compact structure and a complete unit in itself, the unit being arranged within a single casing. However, for certain uses the pump may not be employed, and we consider the invention to be of sufficient scope 100 to embody a starting unit having but the rotor and the transmission mechanism.

While a novel and very efficient construction has been shown and described, we do 105 not desire to limit the protection to the one embodiment of the invention illustrated, but consider the invention to be of sufficient scope to embody various modifications.

What we claim as our invention is:—

1. In a starter, a main casing including a central web having a shaft bearing and side annular rims, one of which rims is eccentric and the other is concentric to said bearing, a cover plate secured to said eccentric rim to 11, form a rotor chamber, a rotor and its pistons mounted within said chamber, means for admitting working fluid into said chamber and exhausting it therefrom, a driving shaft to which the rotor is secured, a second cover plate secured to said concentric rim to 120 close a transmission chamber, said second cover plate having a shaft bearing, a driven shaft mounted in said last named bearing and power transmitting gearing within said 125 transmission chamber for operatively connecting said shafts together.

2. In a starter, a main casing including a central web having a shaft bearing and side annular rims, one of which rims is ec- 130

centric and the other is concentric to said bearing, a cover plate secured to said eccentric rim to form a rotor chamber, a rotor and its pistons mounted within said chamber, means for admitting working fluid into said chamber and exhausting it therefrom, a driving shaft to which the rotor is secured, a second cover plate secured to said concentric rim to inclose a transmission chamber, said second cover plate having a shaft bearing, a driven shaft mounted in said last named bearing and power transmitting mechanisms for operatively connecting said shafts together, said transmitting mechanism including a train of gearing.

3. In a starter, a main casing including a central web having a shaft bearing and side annular rims, one of which rims is eccentric and the other is concentric to said bearing, a cover plate secured to said eccentric rim to form a rotor chamber, a rotor and its pistons mounted within said chamber, means for admitting working fluid into said chamber and exhausting it therefrom, a driving shaft to which the rotor is secured, a second cover plate secured to said concentric rim to inclose a transmission chamber, said second cover plate having a shaft bearing, a driven shaft mounted in said last named bearing and power transmitting mechanisms within said transmission chamber for operatively connecting said shafts together, said transmitting mechanisms including a train of gearing and a self-operating clutch.

35 4. In a starter, a casing including an eccentric and a concentric rim with an internal partition web having a shaft bearing and located between said rims, covers secured to said rims to form respectively a rotor chamber on one side of said partition and a transmission chamber on the other side of the same, a driving shaft and a driven shaft, a rotor within said rotor chamber on said driving shaft, transmission gearing and a clutch device within said transmission chamber for transferring the power of said driving shaft to said driven shaft.

5. In a starter, a casing including an eccentric and a concentric rim with an internal partition web having a shaft bearing and located between said rims, covers secured to said rims to form respectively a rotor chamber on one side of said partition and a transmission chamber on the other side of the same, a driving shaft and a driven shaft, a rotor within said rotor chamber on said driving shaft, a transmission mechanism and clutch device within said transmission chamber for transferring the power of said driving shaft to said driven shaft, said transmission mechanism and clutch device including a driving pinion on the driving shaft, intermediate gears carried by said partition to mesh with said pinion, an internal rim gear meshing with said intermediate gears, a member for carrying said rim gear, and a clutch comprising a member attached to the first mentioned member, a coöperating clutch member fixed to the driven shaft, and connecting elements between the clutch members, the cover of said transmission chamber having a chambered portion to receive said off-set member.

6. In a starter, a casing including an eccentric and a concentric rim with an internal partition web having a shaft bearing and located between said rims, covers secured to said rims to form respectively a rotor chamber on one side of the said partition and a transmission chamber on the other side of the same, a driving shaft and a driven shaft, a rotor within said rotor chamber on said driving shaft, a transmission mechanism and clutch device within said transmission chamber for transferring the power of said driving shaft to said driven shaft, said transmission mechanism and clutch device including a driving pinion on the driving shaft, intermediate gears carried by said partition to mesh with said pinion, an internal rim gear meshing with said intermediate gears, a member for carrying said rim gear, and a clutch comprising a member attached to the first mentioned member, a coöperating clutch member fixed to the driven shaft, and connecting elements between the clutch members.

7. In a starter, a casing including an eccentric and a concentric rim with an internal partition web having a shaft bearing and located between said rims, covers secured to said rims to form respectively a rotor chamber on one side of said partition and a transmission chamber on the other side of the same, a driving shaft and a driven shaft, a rotor within said rotor chamber on said driving shaft, a transmission mechanism and clutch device within said transmission chamber for transferring the power of said driving shaft to said driven shaft, said transmission mechanism and clutch device including a driving pinion on the driving shaft, intermediate gears carried by said partition to mesh with said driving pinion, an internal rim gear meshing with said intermediate gears, a member for carrying said rim gear, and a clutch comprising a member attached to the first-mentioned member, a coöperating clutch member fixed to the driven shaft, and connecting elements between the clutch members.

8. In a starter, a casing including a partition having a bearing and annular rims upon opposite sides of said partition, one of which rims is eccentric and the other concentric to said bearing, cover plates secured to said rims to form respectively a rotor chamber in one side of said partition and a transmission chamber on the other side of the same, a rotor within the rotor chamber, a drive shaft rotated by said rotor, a driven shaft, and transmission mechanism in the transmission chamber forming a driving

100

- connection between the drive and driven shafts.
9. In a starter, a casing having a partition, a rotor within said casing at one side of the partition, a transmission mechanism and a clutch device within said casing at the other side of said partition, a drive shaft fixed to rotate with the rotor, a driven shaft actuable from the drive shaft through said transmission mechanism and clutch device, the inner peripheral wall of the rotor chamber of the casing being eccentric to said drive shaft.
10. In a starter, a casing having an integral partition dividing the same into a rotor chamber and a transmission chamber, a rotor and transmission mechanism respectively arranged in said chambers, covers separately removable to give access to said chambers, and concentric drive and driven shafts, the former being fixed to rotate with the rotor, and the latter being actuable from the drive shaft through said transmission mechanism.
11. In a starter, a casing including a central partition dividing the same into a rotor chamber and a transmission chamber, and rotor and transmission mechanisms respectively arranged in said chambers, a drive shaft fixed to rotate with said rotor, a driven shaft actuated from the drive shaft through the medium of said transmission mechanism, a bearing carried by the partition of one of said shafts projecting laterally into the rotor chamber, said rotor including blades having 35 cut-away portions adjacent their inner ends to receive said bearings.
12. In a starter, a casing, a rotor arranged in said casing, transmission mechanism positioned within the casing, a drive shaft, a 40 driven shaft actuated from the drive shaft through the medium of said transmission mechanism, the two said shafts being concentric and said parts being assembled to form an operative unit.
13. In a starter, a casing formed with two circular chambers, respectively concentric and eccentric to the casing, a transmission mechanism and a rotor respectively arranged in said chambers, a drive shaft fixed 45 to rotate with the rotor, and a driven shaft actuated from the drive shaft through the medium of said transmission mechanism.
